Edward C. Ryer

United States Patent Office.

EDWARD C. RYER, OF BURLINGTON, VERMONT.

Letters Patent No. 78,020, dated May 19, 1868; antedated May 7, 1868.

IMPROVEMENT IN WATCH, CLOCK, AND LOCK-KEYS.

The Schedule referred to in these Letters Patent and making part of the same.

TO ALL WHOM IT MAY CONCERN:

Be it known that I, EDWARD C. RYER, of the city of Burlington, in the county of Chittenden, and State of Vermont, have invented a new and improved Watch, Clock, and Lock-Key; and I do hereby declare that the following is a full and exact description thereof, reference being had to the accompanying drawings, and the letters of reference marked thereon.

The nature of my invention or improvement consists in the manner of operating adjustable watch, clock, and lock-keys.

To enable others skilled in the art to make and use my invention, I will proceed to describe its construction and operation:

I construct the split spring-barrel B of the form as shown, and place thereon the sleeve C, for the purpose of adjusting the barrel B to any desired size. I then add to the sleeve C the winding-ring A, which ring is also used in connection with the sleeve C to adjust the key to proper size. To prevent the sleeve C from sliding up and off the barrel B, I either upset the small end of the barrel simply, or introduce the washer E for that purpose, in the manner shewn by fig. 2. I place upon the barrel B, just above the shoulders F, the ring G, for the purpose of strengthening the key when being used to its largest size.

To use my invention or improvement, lower or raise the sleeve C until the jaws of the barrel B are drawn together or extended to the proper size desired.

Figure 1, view of key open.

Figure 2, longitudinal section on line a B, fig. 3, (key closed.)

Figure 3, bottom of key.

What I claim as my invention, and desire to secure by Letters Patent, is—

1. The manner of applying the sleeve C to the barrel of an adjustable watch, clock, or lock-key, all as herein described and shown, and for the purpose specified.
2. The ring A or its equivalent, as applied to the sleeve C, all as herein shown and described, and for the purpose specified.
3. The ring G, as applied to the barrel B, all as herein shown and described, and for the purpose specified.

EDWARD C. RYER.
